UNITED STATES PATENT OFFICE.

WILLIAM W. WINGER, OF WOLCOTT, INDIANA.

GEARING.

1,070,761.

Specification of Letters Patent. Patented Aug. 19, 1913.

Application filed June 12, 1911. Serial No. 632,599. REISSUED

To all whom it may concern:

Be it known that I, WILLIAM W. WINGER, a citizen of the United States, and a resident of the town of Wolcott, county of White, and State of Indiana, have invented certain new and useful Improvements in Gearing, of which the following is a specification.

My invention relates to improvements in gearing and has for its object the provision of driving mechanism which shall be simple of construction and efficient in operation.

The invention consists in the novel construction and arrangement of parts herein-after described and claimed.

The invention will be best understood by reference to the accompanying drawings forming a part of this specification, and in which, Figure 1 is a top plan view of a washing machine embodying my invention, Fig. 2 is a side elevation thereof, Fig. 3 is a detail vertical section showing a portion of a wringer support employed in the machine, Fig. 4 is a bottom plan view of the machine, and Fig. 5 is an end elevation of the machine showing by dotted lines slidable shelves provided therein in extended position.

The preferred form of construction of my invention as illustrated in the accompanying drawings comprises a table or bench having a top 1, legs 2, and depending side members 3. Mounted upon the table top 1 at one end thereof is a cylindrical clothes receptacle or washer 4 in which the clothes are deposited for washing, access to the interior of said receptacle being effected through a hinged door 5. Rotatably mounted centrally in the washer 4 is an agitator shaft 6 at the lower end of which is provided the revolving agitator 7 as indicated by dotted lines in Fig. 2. The upper end of the shaft 6 is journaled in a bearing strap 8. Carried upon the upper end of the shaft 6 just below the strap 8 is a spur pinion 9 which meshes with and is driven by a segment-gear 10, which in turn is fulcrumed at 11 to one end of the cover 5, the arrangement being such that upon oscillation of the arm 12 formed integral with the gear 10, said agitator 7 will be oscillated to effect the cleansing of the clothes which are brought into contact therewith in the receptacle 4. Mounted in the table or bench 1 adjacent the receptacle 4 is a vertically disposed shaft 13 carrying a circular crank

disk 14 at its upper end. A crank pin 15 is operatively connected through the medium of the link 16 with the outer or free end of the arm 12, the arrangement being such that rotation of said crank pin effects oscillation of the gear 10 and consequently the agitator 7. A plurality of perforations 16' is provided at the outer end of the arm 12 whereby the extent of oscillation of the segment-gear 10 may be varied. Provided at the lower end of the shaft 13 is a crown gear 17 which meshes with a bevel gear 18 loosely mounted on the driving shaft 19, the latter being driven by means of a pulley 20 as will be readily understood by those skilled in the art. Operative connection between the shaft 19 and the gear 18 is effected through the medium of a slidable clutch 21 which is provided with a peripheral groove for engagement with a shifting rod 22, there being intermeshing teeth 22' provided in the gear 18 and clutch 21 for effecting the locking of these parts upon longitudinal movement of the clutch. Also journaled in the table 1 is a vertically disposed shaft 23 upon the upper end of which is loosely mounted for angular adjustment an ordinary clothes wringer 24, operative connection between the rollers 25 of said wringer being effected through the medium of meshing beveled pinions 26. The wringer 24 is adapted to be adjusted in a horizontal plane to any angular position, the same being held in any position of adjustment by means of a pin 26' which passes through a perforated ear 26" formed integral with the frame or standard of said wringer, said pin being adapted to engage any one of the plurality of perforations 27 provided in a circular index plate 28 which is arranged in a plane below the ear 26". Provided at the lower end of the shaft 23 is a crown gear 29, operative connection between said crown gear and the driving shaft 19 being effected through beveled pinions 30 and 31 which are loosely mounted upon said shaft 19. Operative connection between the pinions 30 and 31 and said shaft 19 is effected through the medium of a slid-able clutch 32 which may be moved into engagement with either of said pinions as desired to effect the connection thereof with said shaft 19, there being a shifting lever or rod 33 which engages with a peripheral groove 33' provided in the clutch 32 for moving the same longitudinally. The

clutches 21 and 32 are splined to the shaft 19 to prevent rotation thereof when in any longitudinal position thereon. With this arrangement it will be seen that the gear 29 5 may be driven in either direction as desired and the wringer rollers 25 correspondingly driven.

Slidably mounted upon the under side of the table top in guides 34 are leaves 35 which 10 may be drawn out for use in holding a tub of water or a basket of clothes as the case may be.

A handle 36 is provided on the lid 5 of the receptacle 4, whereby the same may be readily 15 lifted for the placing in or removal of clothes from the receptacle.

The mode of operation of this washing machine is as follows: Assuming that the receptacle 4 is filled or partially filled with 20 clothes and suds and that the power shaft 19 is being rotated at a constant speed, then in order to actuate the oscillatory agitator 7 of the washer, the shift lever 22 is moved in the direction necessary for the engagement 25 of the clutch 21 with the bevel gear 18 whereupon the clothes will be agitated and washed in the receptacle 4. After the clothes have been sufficiently cleansed in the 30 washer, the shift lever 22 is moved in the opposite direction thus stopping the agitator 7, whereupon the lid 5 may be opened by means of the handle 36 and the clothes moved to a basket provided therefor and supported by one of the leaves 35 adjacent the 35 washer. The wringer 24 may now be swung into a position at right angles with the bench 1 ready to receive the clothes in the wringing process. The shift lever 33 is now moved in such a direction as to effect the engagement 40 of the clutch 32 with either the bevel gear 30 or 31 according to the direction which it is desired to have the rollers 25 of the wringer rotate. The clothes in the basket are then fed to the rollers 25, and 45 after being discharged therefrom are received in a basket, not shown, supported by the other shelf 35 thus completing the washing operation.

Any suitable power may be provided for 50 the actuation of the shaft 19, such a gasolene engine, electric motor, or a suitable steam en-

gine. A washing machine of the construction set forth is compact and symmetrical in design; simple of construction, strong and durable, and capable of performing all 55 of its functions in an efficient and reliable manner.

While I have illustrated and described the preferred form of construction for carrying my invention into effect, this is capable 60 of variation and modification without departing from the spirit of my invention. I therefore, do not wish to be limited to the precise details of construction as set forth, but desire to avail myself of such variations 65 and modifications as come within the scope of the appended claims.

Having described my invention what I claim as new and desire to secure by Letters Patent is:

1. A driving mechanism comprising a horizontal shaft; a bevel gear loosely mounted on said shaft; a clutch splined to said shaft and adapted to clutch said bevel gear; a vertical shaft and at its lower end a bevel 75 gear in mesh with said first mentioned bevel gear; a crank pin on the upper end of said vertical shaft; a lever arm; a segmental gear on said lever arm; a pinion meshing with said segmental gear; and a link connection 80 between said lever arm and said crank pin, substantially as described.

2. A driving mechanism comprising a horizontal shaft; a bevel gear loosely mounted on said shaft; a clutch splined to said 85 shaft and adapted to clutch said bevel gear; a vertical shaft, and at its lower end a bevel gear in mesh with said first mentioned bevel gear; a crank pin on the upper end of said vertical shaft; a lever arm; a segmental 90 gear on said lever arm; a pinion meshing with said segmental gear; and an adjustable link connection between said lever arm and said crank pin, substantially as described.

In testimony whereof I have signed my name to this specification in the presence of two subscribing witnesses.

WILLIAM W. WINGER.
